UNITED STATES PATENT OFFICE.

CHARLES E. BUTLER, OF NEW YORK, N. Y.

RIPPING-SCISSORS.

SPECIFICATION forming part of Letters Patent No. 581,656, dated April 27, 1897.

Application filed August 13, 1896. Serial No. 602,592. (No model.)

To all whom it may concern:

Be it known that I, CHARLES E. BUTLER, a citizen of the United States, residing at New York, in the county of New York and State 5 of New York, have invented certain new and useful Improvements in Ripping-Scissors, of which the following is a specification.

My invention relates to a new and useful improvement in ripping-scissors, and has for 10 its object to provide a device of this description by means of which a seam may be ripped without care upon the part of the operator to spread the edges of the goods in exposing the stitching and which will greatly facilitate the 15 heretofore tedious operation of separating seams by ripping; and with these ends in view my invention consists in the details of construction and combination of elements hereinafter set forth, and then specifically designated by the claims.

In order that those skilled in the art to which this invention appertains may understand how to make and use the same, I will describe its construction and operation in detail, referring by letter to the accompanying drawings, forming a part of this specification, and in which—

Figure 1 is a perspective of my improvement; Fig. 2, a plan view; and Fig. 3, a section removing one of the spring-plates, the handle being partly broken away.

In carrying out my invention I provide two plates A and B, which are similar in all respects and are preferably composed of spring 35 material, such as steel or brass, and these plates are secured within the handle C in any ordinary manner. Formed upon the outer ends of the plates are guide-strips D and guard projections E, the former projecting 40 from the lower edges of the plates and the latter from the upper edges thereof, and in practice I prefer to so bend the guards as to cause them to present a slightly-rounded cross-section at the point of union with the plates A and B. Secured within the handle 45 between the plates is a stationary scissors-blade F by its shank G being driven or set within said handle, and pivoted to this stationary blade at H is a swinging blade I, the latter terminating in a handle J, having a thumb-button K upon its inner end, the spring L serving to hold the swinging blade normally 50 in its open position relative to the stationary blade.

The distance between the two plates A and B is regulated by a screw M, which is threaded into the latter and provided with a knurled head N, adapted to bear against the plate A and permit the screw to be revolved. This screw also passes through the shank of the 60 stationary blade, which arrangement facilitates the holding of said plates in proper alignment with said blade.

From this description the operation of my improvement will be obviously as follows: A 65 small hole is first made if a seam is to be started other than at the end of the fabric, the point of one of the blades inserted within said opening, and the ends of the plates A and B also inserted within said opening, so 70 that the strips D will lie below the fabric and the guards E above the same, when by a forward movement of the device with the right hand while the ends of the fabric are held with the left hand the edges of the seam will 75 be pressed sidewise, so as to clearly expose to view the threads which form the stitching, so that it is only necessary to manipulate the blade I by alternately pressing upon the button K and permitting the spring to move said 80 blade in the opposite direction to sever the threads and thus ripping the seam. The guards E at all times turn the edges of the fabric outward and thus prevent the obscuring of the threads during the operations of 85 the device. The extent to which the edges of the seam are flared or pressed open is determined by the adjustment of the plates A and B, which is regulated by the proper manipulation of the screw N, as before described. 90 From this it will be seen that my improvement greatly facilitates the tedious work of ripping, since instead of having to force the goods apart by the first finger and thumb of the lefthand in the effort to expose the threads 95 the ripping-scissors do this by forcing the fabric open by the mere pushing of the handle, thereby exposing said threads without any effort on the part of the operator.

One of the advantages of the construction 100 here shown is that the leverage is greatly in favor of the operations of the scissors in that the distance from the point of said scissors to the pivot-point H is very small relative to

the distance from said point to the button K, where the power is applied.

Should at any time the person become wearied in operating the lever J by the thumb, 5 the device may be turned upside down and said lever be operated by the first finger, and this is of considerable importance with dress-makers and others where a large number of seams have to be ripped and the hand of necessity becomes wearied with any one motion.

Having thus fully described my invention, what I claim as new and useful is—

1. A ripping device consisting of two plates, 15 guide and guard strips projecting therefrom, means for adjusting the plates and a pair of scissors located between the plates and supported by the adjusting means, substantially as described.

2. A pair of ripping-scissors, consisting of 20 two plates, a screw for regulating the distance between said plates, a pair of scissors located between said plates, and a handle to which said plates and scissors are secured, substantially as shown and described.

25 3. The combination of the plates A and B secured within a suitable handle, a stationary

blade also secured within said handle, a swinging blade pivoted to the first-named blade, a spring for holding said swinging blade open, guide-strips projecting from said plates, and guards also projecting from said plates, substantially as and for the purposes set forth. 30

4. The herein-described combination of the handle C, a stationary blade F secured within said handle, spring-plates A also secured within said handle, a screw M passing through one of said plates and the blade and threaded into the opposite plate, a swinging blade pivoted to the first-named blade, a spring L 40 adapted to hold the last-named blade in its open position, a button K for closing said blade, guide-strips D projecting from the outer ends of the plates, and the guards E also projecting from said plates, all arranged substantially as and for the purpose set forth. 45

In testimony whereof I have hereinunto affixed my signature in the presence of two subscribing witnesses.

CHARLES E. BUTLER.
